UNITED STATES PATENT OFFICE.

DORR F. LOUDON, OF NEW YORK, N. Y.

METALLIC WASHTUB COVER.

Application filed August 24, 1915. Serial No. 47,054.

To all whom it may concern:

Be it known that I, DORR F. LOUDON, a citizen of the United States, and a resident of the city of New York, borough of Manhattan, in the county and State of New York, have invented a new and Improved Metallic Washtub Cover, of which the following is a full, clear, and exact description.

The object of the invention is to provide a new and improved metallic washtub cover which is exceedingly strong and durable and not liable to warp and lose its shape even when weighted with cooking utensils or other articles. Another object is to prevent water or any other liquid from running onto the floor especially such liquids as may run off wet cooking utensils set on the cover. Another object is to prevent water of condensation or dirt from accumulating and 20 adhering to the inside of the cover and to allow of conveniently cleaning the cover to render the same sanitary and to readily keep it in this condition.

In order to produce the desired result the washtub cover is made of a single piece of sheet metal and having a body portion provided with a central depression, and a continuous flange of uninterrupted continuity depending integrally from the margin of the body portion at approximately a right angle thereto, the flange having its lower edge in a plane below that of the under side of the depression.

A practical embodiment of the invention is represented in the accompanying drawings forming a part of this specification, in which similar characters of reference indicate corresponding parts in all the views.

Figure 1 is a plan view of the metallic washtub cover;

Figure 2 is a sectional side elevation of the same on the line 2-2 of Figure 1;

Figure 3 is a cross section of the same on the line 3-3 of Figure 1;

Figure 4 is a plan view of the sheet metal blank from which the cover is struck up; and

Figure 5 is an enlarged sectional side elevation of a portion of the washtub cover.

The washtub cover is made of a single piece of sheet metal 10 cut to a desired shape and size and provided near the opposite edges with apertures 11 and 12, as plainly indicated in Figure 4. The blank is subjected to pressing operations by suitable machinery to form a cover having a body

portion 13 provided with a central depression 14 for retaining water or other liquid that may pass from wet cooking vessels or other articles set on the cover at the time the latter is in closed position on the washtub. From the marginal edges of the body portion 13 depends a flange 15 of uninterrupted continuity, the flange extending integrally from the body portion 13 approximately at a right angle thereto, the lower edge of the flange being in a plane below that of the under side of the depression 14, as plainly indicated in Figures 2 and 3. The upper and under surfaces of the body portion 13, its depression 14 and the continuous flange 15 are covered with a coating 16, preferably of vitreous enamel, to render the cover exceedingly smooth and at the same time give a highly finished appearance to the cover. The continuous flange 15 is rounded off at the corners and the joint between the margin of the body portion 13 and the flange 15 is likewise rounded off so as to reduce the adherence of extraneous matter to a minimum. The apertures 11 and 12 previously mentioned extend in the rear and front portions of the flange 15 to permit of connecting the usual hinges 17 with the flange at the rear thereof and to connect the usual bumpers or cushions 18 to the front portion of the flange, as plainly indicated in Figures 1 and 3.

The material employed is preferably sheet steel, and by constructing the cover in the manner above set forth, the cover is rendered exceedingly strong and durable, and is capable of supporting various articles without danger of warping or bending the cover, it being understood that during the time the cover is in closed position on the washtub it is used by housekeepers as a shelf for the support of kitchen utensils, groceries and other articles. Any water or other liquid that may run off the supported wet cooking utensils and other articles readily accumulates in the depression 14 and is hence not liable to run off to the floor and soil the same. It will be noticed that by rendering the cover exceedingly smooth on both faces dirt and other extraneous matter is not liable to adhere to the cover and the latter can be readily cleaned especially at the rounded off corners to render the metallic washtub cover sanitary and to keep it in this condition.

It will further be noticed that by manu-

facturing the cover in the manner described no undesirable joints, folds, crevices or the like are formed to prevent the accumulation and adherence of dirt and other extraneous matter.

Having thus described my invention, I claim as new and desire to secure by Letters Patent:

In a one piece metallic washtub cover, having seamless corners, downwardly projecting edges having perforations therein, bolts adapted to be passed through certain perforations, a bumper secured to the cover by

said bolts, means for hingedly connecting the cover to the tub, and bolts passing through other perforations on the opposite edge of the cover for securing the last mentioned means to the cover.

In testimony whereof I have signed my name to this specification in the presence of two subscribing witnesses.

DORR F. LOUDON.
